BURNER AND FUEL CONTROL MECHANISM

David Lumsden, Sikeston, Mo.

Original application December 21, 1935, Serial No. 55,644. Divided and this application December 22, 1936, Serial No. 117,195

6 Claims. (Cl. 158—84)

This invention relates to an improved burner and mechanism for controlling flow of fuel to the same and while it is particularly adapted for use as a burner for a water heater it is to be understood that it may be used wherever found practical. The present application constitutes a division of my co-pending application for a patent upon an improved Burner and fuel control filed December 21, 1935; Serial No. 55,644.

One object of the invention is to provide a burner adapted to burn liquid fuel, such as coal oil, the burner including a main wick and an auxiliary wick so associated with the main wick that fuel may be supplied either to only the auxiliary wick or both the main wick and the auxiliary wick.

Another object of the invention is to so mount the auxiliary wick which may be referred to as a pilot light that fuel fed through a single pipe may be supplied to the auxiliary wick and the main wick and thus make it unnecessary to provide a supply pipe for each wick.

Another object of the invention is to so construct and mount the fuel supply means that fuel may be supplied to the auxiliary wick after oil in the pan carrying the main wick and into which the auxiliary wick extends has been reduced by consumption to such an extent that the main wick will become extinguished.

Another object of the invention is to provide the burner with improved means for controlling the length of time the main wick will burn after flow of fuel from a source of supply has been shut off, the said means being of such construction that adjustment may be very easily made.

The invention is illustrated in the accompanying drawing, wherein the figure shows the improved burner and the fuel supply and regulating mechanism partially in side elevation and partially in vertical section.

In the accompanying drawing, the numeral 10 indicates the lower portion of a water heater in which the improved burner is mounted and it will be understood that this heater may be of any desired construction which will permit water to be heated by hot products of combustion passing upwardly through the same from the burner which is mounted in the lower portion of the heater. This burner has an annular fuel pan 11 which is U-shaped in cross section and open at its top. It carries the usual chimney or hood 12 and combustion tubes, as shown in the co-pending application referred to above, and it also carries a main wick 13 and an auxiliary wick 14. The auxiliary wick is disposed vertically in

the fuel pan between ends of the main wick and its lower portion extends downwardly through an opening formed in the bottom of the fuel pan into a nipple 15. It should be noted that this auxiliary wick extends downwardly into the enlarged lower portion 16 of the nipple so that oil may accumulate in the nipple about the lower portion of the auxiliary wick and a portion of this oil move upwardly through the wick into the fuel pan to supply fuel to the main wick when both the main wick and the auxiliary wick are burning. A metal casing 17 has been shown provided about the auxiliary wick as disclosed in the co-pending application referred to above, and it is to be understood that this casing has its lower portion open, as shown at 18, so that oil in the nipple can easily reach the wick. The upper portion of the casing is formed with side openings so that oil may flow through the side openings and into the fuel pan.

In order to supply fuel to the nipple, there has been provided a pipe 19 leading from the depending neck 20 of a cup 21 which is mounted at one side of the heater 10. An elbow 22 is threaded upon the other end of the fuel pipe 19 to project upwardly therefrom and this elbow has threaded engagement with the lower portion 23 of a union 24 which projects upwardly therefrom and has its upper portion 25 in threaded engagement with the nipple. The pipe 19 is provided with an upwardly extending arm or branch 26 which projects upwardly into the lower end of the heater and at its upper end carries a cup 27 serving as an auxiliary oil chamber. This cup or auxiliary chamber is formed with an opening 28 in its bottom through which oil may flow and the upper end of the cup is closed by a removable cap 29 which is preferably threaded into place but may be removably secured in any manner desired. It is desired to permit the capacity of the cup to be

varied according to the length of time it is desired to have the main wick burn after flow of oil has been automatically shut off and in order to do so walls of the cup carry inwardly extending lugs or blocks 30 which are preferably three in number and serve as supports for a disc 31 which constitutes one of a number of discs of various thicknesses and has its lower face slightly below the level of the bottom of the oil pan when in place. When a relatively thin disc is set in place only a small portion of the capacity of the cup will be taken up by the disc, whereas when a thicker disc is substituted in place of a thin disc a larger portion of the interior of the cup will be taken up by the disc and a proportionately smaller quantity

of oil will be required to fill the cup to the level of the line A—A. It will thus be seen that by substituting a thick disc in place of a thin disc, the quantity of oil in the auxiliary chamber can be reduced and the length of time the main wick will burn, after flow of oil has been shut off, regulated.

The cup or chamber 21 extends upwardly above the level of the cup 27 and at its upper end is closed by a cap or head 32 formed with an upwardly extending neck 33 with which a pipe 34 is connected. This pipe 34 extends from a suitable source of fuel supply and the fuel flows through the neck into the cup 21 and through 15 perforations of the tube 35 into the passage 36 of the neck 20. From this passage 36 the oil flows through the pipe 19 and from this pipe into the auxiliary chamber or cup 27 and also through the nipple 15 and the tubular casing of the auxiliary wick into the oil pan or trough 11. A perforated disc 37, which serves as a valve seat, is secured in the passage 36 under the lower end of the tube 35 when this tube is screwed tightly into place and through this tube extends a stem 25 38 having a spherical head 39 at its lower end and which serves as a valve and shuts off flow of oil from the tube 35 into the passage 36 when seated against the valve seat 37. At its upper end the stem 38 is pivoted to one end of an arm 30 40 which has its other end pivoted to a support 41 mounted externally of the burner in any desired manner and the lower end of a rod 42 is pivoted to the arm 40 near the pivotally mounted end thereof. This rod 42 constitutes part of a 35 conventional mechanism having a thermostat associated therewith which will cause the arm to move downwardly when water which is being heated attains a predetermined temperature and it will thus be seen that, when the predetermined temperature has been reached, the arm 40 will 40 be swung downwardly to lower the stem 38 and move the valve to a seated position in which flow of oil through the passage 36 will be shut off. When this occurs, the main wick will continue 45 burning until the level of the oil which is normally at the height, indicated by the dot and dash line A—A, has been reduced to such a level that it is below the lower end of the main wick 13 and this wick will then be extinguished due to lack of fuel. The pilot wick will, however, 50 continue burning as its lower portion will still be immersed in oil and, therefore, when the temperature of the water has been reduced to a predetermined temperature at which time the rod 42 will be drawn upwardly and move the valve 39 off the seat, oil will again flow through the 55 passage 36 into the pipe 21 and fill the auxiliary chamber 27 and oil pan 11 to the normal level in which oil will be fed to the main wick 13 and the main wick then ignited from the pilot wick. Oil in the main chamber or cup 21 is to be maintained at the normal level, indicated by the dot and dash line previously referred to, and in order to do so, there has been provided a float 43 which 60 is pivoted to a depending hinge ear 44 carried by the cap 32 at one side of the bore 45 of the neck 33. The bracket 46, by means of which the float is pivotally connected to the ear 44, has one portion bent to form a leaf 47 and this leaf, 65 which is disposed in overhanging relation to the bracket and is formed of resilient material, carries an upwardly extending needle valve 48 adapted to enter and close the opening 49 formed in a disc 50 mounted in the neck 33 and defining an upper chamber 51 from which the bore 45

leads. It will thus be seen that, when the float is moved upwardly by oil in the main chamber or cup 21 to the position shown in the drawing, the needle valve by entering the opening 49 will shut off flow of oil from the chamber 51 and as the oil is consumed the float will be moved downwardly until the needle valve is moved to an open position in which it allows additional oil to flow into the main chamber. Therefore, oil in the main chamber will be maintained at the desired level and oil fed to the trough or oil pan 11 until the water has been heated to the desired temperature at which time the valve 39 will be closed to shut off flow of oil through the passage 36 into the pipe 19. The main wick will then continue to burn until oil in the auxiliary chamber and the oil pan has been reduced to such a level that oil is no longer present in the oil pan and the wick 13 will then be extinguished. This only takes a few minutes, the length of time being 20 regulated according to the thickness of the disc 31. When the main wick is extinguished, the auxiliary wick or pilot continues to burn so that, when the water has cooled to such a temperature that the valve 39 will be again moved upwardly 25 to permit flow of oil through the passage 36, the main wick will be ignited.

Having thus described the invention, what is claimed as new is:

1. A burner including a fuel pan having a fuel inlet opening at its bottom, a fuel chamber having a valve controlled inlet at its top, a fuel pipe leading from the bottom of the fuel chamber for supplying fuel to the fuel pan through the inlet thereof, an auxiliary fuel chamber above the fuel pipe having an outlet at its bottom communicating with the fuel pipe between the fuel chamber and the fuel pan, a valve for controlling flow of fuel from the fuel chamber through the fuel pipe into the auxiliary chamber and the fuel pan, float controlled means in the fuel chamber for closing the inlet valve thereof and preventing filling of the fuel chamber, auxiliary chamber and the fuel pan with fuel beyond a predetermined level, and removable means in the auxiliary chamber for controlling the effective capacity of the auxiliary chamber.

2. A burner comprising a fuel pan having a fuel inlet at its bottom, a fuel chamber spaced laterally from said fuel pan and having an upper portion above the plane of the bottom of the fuel pan, said chamber having a fuel inlet, a fuel pipe leading from said fuel chamber to the fuel inlet of said fuel pan, an auxiliary fuel chamber above the fuel pipe extending upwardly above the plane of the bottom of the fuel pan and having an outlet at its bottom communicating with the fuel pipe, float controlled means for controlling flow of fuel into the fuel chamber, a valve for controlling flow of fuel from the fuel chamber through the fuel pipe, and a removable body in the auxiliary fuel chamber for displacing a predetermined quantity of fuel above the plane of the bottom of the fuel pan.

3. A burner comprising a fuel pan having a fuel inlet at its bottom, a fuel chamber spaced laterally from said fuel pan and having an upper portion above the plane of the bottom of the fuel pan, said chamber having a fuel inlet, a fuel pipe leading from said fuel chamber to the fuel inlet of said fuel pan, an auxiliary fuel chamber above the fuel pipe extending upwardly above the plane of the bottom of the fuel pan, an arm connecting the fuel pipe with an outlet at the bottom of the auxiliary fuel chamber, float con-

trolled means for controlling flow of fuel into the fuel chamber, a valve for controlling flow of fuel from the fuel chamber through the fuel pipe, supporting means in the auxiliary fuel chamber, 5 and a removable body deposited in the auxiliary fuel chamber through the upper end thereof and resting upon said supporting means and adapted to displace a predetermined quantity of fuel above the plane of the bottom of the fuel pan.

10 4. A burner comprising a fuel pan having a fuel inlet at its bottom, a fuel chamber spaced laterally from said fuel pan and having an upper portion above the plane of the bottom of the fuel pan, said chamber having a fuel inlet, a fuel pipe leading from said fuel chamber to the fuel inlet of said fuel pan, an auxiliary fuel chamber above the fuel pipe extending upwardly above the plane of the bottom of the fuel pan, an arm connecting the fuel pipe with an outlet at the bottom of the 15 auxiliary fuel chamber, float controlled means for controlling flow of fuel into the fuel chamber, a valve for controlling flow of fuel from the fuel chamber through the fuel pipe, lugs extending from walls of the auxiliary chamber intermediate upper and lower ends thereof, and a disc deposited in the auxiliary chamber through the upper end thereof and resting upon said lugs and being adapted to displace a predetermined quantity of fuel above the plane of the bottom of the 20 fuel pan.

25 5. A burner comprising a fuel pan having a fuel inlet at its bottom, a fuel chamber spaced laterally from said fuel pan and having its upper end above the plane of the bottom of the fuel pan, said chamber having a fuel inlet, a fuel pipe leading from said fuel chamber to the fuel inlet of said fuel pan, an auxiliary fuel chamber above 30 the fuel pipe extending upwardly above the plane of the bottom of the fuel pan, an arm connecting the fuel pipe with an outlet at the bottom of the auxiliary fuel chamber, a removable body in the auxiliary fuel chamber for displacing a predetermined quantity of fuel above the plane of the bottom of the fuel pan, a perforated tube extending vertically in the fuel chamber from the outlet and having a valve seat at its bottom, a valve operating through said tube for controlling flow 35 of fuel through the fuel pipe, a float pivotally mounted in said fuel chamber about said tube, and a valve carried by said float to shut off flow of fuel into the fuel chamber when the float is raised to a predetermined height.

the fuel pipe extending upwardly above the plane of the bottom of the fuel pan, an arm connecting the fuel pipe with an outlet at the bottom of the auxiliary fuel chamber, a removable body in the auxiliary fuel chamber for displacing a predetermined quantity of fuel above the plane of the bottom of the fuel pan, a perforated tube extending vertically in the main chamber from the outlet and having a valve seat at its bottom, a valve operating through said tube for controlling flow of fuel through the fuel pipe, and float controlled means for controlling flow of fuel into the fuel chamber.

6. A burner comprising a fuel pan having a fuel inlet at its bottom, a fuel chamber spaced laterally from said fuel pan and having its upper end above the plane of the bottom of the fuel pan, said chamber having a fuel inlet, a fuel pipe leading from said fuel chamber to the fuel inlet of said fuel pan, an auxiliary fuel chamber above the fuel pipe extending upwardly above the plane of the bottom of the fuel pan, an arm connecting the fuel pipe with an outlet at the bottom of the auxiliary fuel chamber, a removable body in the auxiliary fuel chamber for displacing a predetermined quantity of fuel above the plane of the bottom of the fuel pan, a perforated tube extending vertically in the fuel chamber from the outlet and having a valve seat at its bottom, a valve operating through said tube for controlling flow of fuel through the fuel pipe, a float pivotally mounted in said fuel chamber about said tube, and a valve carried by said float to shut off flow of fuel into the fuel chamber when the float is raised to a predetermined height.

DAVID LUMSDEN.
